UNITED STATES PATENT OFFICE.

PETER BROWN, OF CHICAGO, ILLINOIS, ASSIGNOR TO O-CEDAR CORP'N, OF CHICAGO, ILLINOIS, A CORPORATION OF ILLINOIS.

MOP HEAD.

Application filed February 26, 1925. Serial No. 11,627.

This invention relates to a mop head and concerns itself with a device around which the mop extends, together with means for supporting and expanding the mop for quick assembly and disassembly.

The invention comprises the novel structure and combinations hereinafter described and more particularly pointed out and defined in the appended claims.

10 In the accompanying drawings which illustrate a preferred embodiment of this invention and in which similar reference numerals refer to similar features in the different views:

15 Figure 1 is a top plan view of the assembled mop.

Figure 2 is an enlarged longitudinal and vertical sectional view of the mop.

20 Figure 3 is an enlarged transverse sectional view of the mop taken substantially upon the line III—III of Figure 1.

Figure 4 is an enlarged sectional detail view with parts in elevation showing the expanding mechanism for clamping the mop 25 upon the head.

Figure 5 is an enlarged sectional view through the mop head showing the expanding mechanism in plan view with the mop omitted.

30 Referring to the drawings which illustrate one form of this invention, it will be observed that the mop head comprises an oblong metal member having a top 1 with depending side flanges 2 which curve toward each other at their ends as indicated at 2°. The ends of the flanges, however, are spaced apart to allow terminal mop supporting hook members 3 to project therebetween. These hook members 3 in the present instance are shown as 35 separate members attached to the lower surface of the top 1 of the mop head.

Upon one side of the mop head there projects a stud 4. This stud is preferably a separate member attached to a depending 45 flange 2. It is adapted for receiving an eyelet or the like in the attaching portion of the mop. Upon the opposite side of the mop there projects the expanding mechanism for the mop. In the illustrated form of this invention, this expanding mechanism consists 50 of a pair of actuated lever members or fingers 5 which are co-axially pivoted at their rear or inner ends upon a pivot pin 6, and which are simultaneously actuated by a 55 screw member 7 threaded into a slid able

block 8 which is suitably slotted for receiving the members 5.

The particular manner of pivoting the members 5 may be accomplished in various ways. In the present instance, however, a 60 slot is provided in the rear flange 2 through which the ends of the lever members 5 project and the pin 6 is welded to the exterior of the flange 2 and extends through a suitable eyelet punched in said flange as shown in 65 Figure 4.

The forward ends of the lever members 5 project through suitable slots in the front flange 2 and the screw 7 also extends through such front flange. The outer portion of the screw is provided with a suitable operating handle 9 having a collar 10 seated against the flange 2.

70 The mop 11 which may consist of any suitable material comprises a folded strip of sufficient length to surround the mop head. The folded portion is enclosed by a fabric binding which is tucked in at the ends of the mop. Suitable eyelets 12 are fastened in the ends of the fabric binding, and a suitable eyelet 13 is fastened in the middle of the length of the fabric binding. Upon the top of the head, there is secured a socket 75 14 adapted for receiving the mop handle.

In assembling the mop with respect to its 80 head, the eyelet 13 is secured to the peg 4, the opposite halves of the bound margin of the mop are then wrapped around the head, suspended upon the hook supports 3 and the eyelets 12 positioned upon the arms 5. The 85 screw 7 may now be actuated to draw the block 8 outwardly and bring the arms 5 together. This operation will tightly bind the 90 mop upon the head as is obvious. To remove the mop, it is only necessary to operate the screw 7 in the opposite direction to 95 allow the arms 5 to separate for removing the tension of the mop around the head, allowing the ends to be removed from the arms 5.

100 It will be appreciated that the mop head is exceedingly simple and light, and is susceptible of firmly sustaining the mop under a reasonable amount of tension. It will also be appreciated that the mop can be readily removed and a new one applied as occasion requires.

105 I am aware that many changes may be made, and numerous details of construction may be varied through a wide range without 110

departing from the principles of this invention, and I therefore do not purpose limiting the patent granted hereon, otherwise than necessitated by the prior art and the appended claims.

I claim as my invention:

1. A mop head comprising an oblong metal member having depending side flanges, mop engaging means projecting between said flanges, a pair of fingers having a common pivot on one flange and projecting through the other flange, a slidable block on said fingers and a screw for actuating said slidable block.
- 10 2. A mop head comprising a member having means around its periphery to which the

mop is adapted to be engaged, a pair of actuatable fingers having a common pivot on said member and adapted for engaging the ends of the mop, a slidable block on said fingers and a screw threaded in said block for actuating the latter.

20 3. A mop head comprising a member having means around its periphery for supporting a mop, a pair of fingers having a common pivot on said member and adapted for engaging at their free ends the ends of the mop, and manually operated means for moving said fingers toward or from each other.

25 In testimony whereof I have hereunto subscribed my name.

PETER BROWN.
